UNITED STATES PATENT OFFICE.

GEORGE W. MITTELSTAEDT, OF MORTON GROVE, ILLINOIS, ASSIGNOR TO FLY ESCAPE SCREEN COMPANY, OF CHICAGO, ILLINOIS, A CORPORATION OF ILLINOIS.

FLY-ESCAPE SCREEN.

1,378,601.

Specification of Letters Patent. Patented May 17, 1921.

Application filed June 4, 1920. Serial No. 386,551.

To all whom it may concern:

Be it known that I, GEORGE W. MITTELSTAEDT, a citizen of the United States, residing at Morton Grove, in the county of 5 Cook and State of Illinois, have invented certain new and useful Improvements in Fly-Escape Screens, of which the following is a specification.

The invention relates to improvements in 10 fly escape screens, and particularly to screen doors and other screens adapted to permit the escape of flies or the like from the interior of a room.

The object of the invention is to provide 15 an improved construction which may be easily and cheaply manufactured for permitting the escape of flies through screen doors or other screens, which fit within a surrounding door or similar frame.

20 A further object is to provide a paneled door or screen of simple construction, adapted to permit the escape of flies or the like through a lower panel, as well as the upper panel.

25 The invention consists in the novel arrangements, combinations and constructions, to be hereinafter described, and claimed, for carrying out the above stated objects, and such other objects as will appear from the 30 following description.

The invention is illustrated in a preferred embodiment in the accompanying drawing, wherein:

Figure 1 is an elevation of a door or 35 screen embodying the principles of my invention;

Fig. 2 is a fragmentary vertical section taken on the line 2—2 of Fig. 1;

Fig. 3 is an enlarged elevation of the 40 upper portion of the screen shown in Fig. 1; and

Fig. 4 is a transverse section taken on the line 4—4 of Fig. 3.

Fig. 5 is an enlarged elevation of the central portion of the screen including the 45 transverse panel rail;

Fig. 6 is a transverse section taken on the line 6—6 of Fig. 5;

Fig. 7 is a transverse section taken on the 50 line 7—7 of Fig. 5; and

Fig. 8 is a fragmentary vertical section taken along the line 8—8 of Fig. 1.

Like characters of reference designate

like parts in the several figures of the drawings.

In the drawings, 10 represents a screen comprising side stiles 11, upper rail 12, lower rail 13, and transverse panel rail 14. The frame members may be of any suitable material, such as wood or metal. For the 60 purpose of illustration I have shown a frame composed of some solid material, such as wood. The transverse rail 14 divides the screen into upper and lower panels 15 and 16, provided with any suitable screening 65 material 17. The screen may be divided into any number of panels.

The upper rail 12 is provided with a longitudinal channel or cavity 18 formed in the outer face of the rail. Another channel or 70 recess 19 is provided in the rail above the channel 18 and spaced therefrom. Connecting the two channels 18 and 19 is a series of fly escape passages 20, formed in the rail, and of a size adapted to permit the passage 75 of a fly or other insect. Leading to the lower edge of the rail is another series of fly escape passages 21, which connect the channel 18 with the interior of the frame. These passages are preferably staggered 80 with respect to the upper series of passages 20.

The transverse panel rail 14 is also preferably formed with channels 22 and 23 and fly escape passages 24 and 25, similar in construction to the corresponding channels and 85 passages in the rail 12. If desired, the rails 12 and 13 may be duplicates. The screening in the lower panel extends to the lower edge of the channel 23, covering the channel 22 90 and the passages 24 and 25. The screening material in the upper panel 15 is secured at its lower edge to the upper margin 26 of the rail 14 and extends to the lower edge of the channel 19 in the same manner as in the 95 lower panel 16, and covers the channel 18 and the passages 20 and 21. Suitable fastening elements 27 are used to secure the screening to the frame, and are preferably also placed adjacent the edges of the fly escape 100 passages, as shown. Suitable finishing strips 28, preferably cover the side edges and lower edges of the screening material in the panels 15 and 16 respectively. Preferably no finishing strips are used along the 105 upper edges of the screening material form-

ing the various panels, so as not to cast any shadow across the fly escape passages 20 and 24. In devices of this character, flies will not pass through a shaded or dark passage 5 or across a shaded line.

It will be noted that a gap is provided between the screening in the upper and lower panels, or between adjacent panels, in case more than two are provided, in order that 10 the channel 23 may remain uncovered, so as not to interfere with the escape of the flies.

In this construction advantage is taken of the instinct of flies and similar insects to climb upwardly and be attracted toward 15 light. Accordingly flies which may be found on the interior of the screen tend to climb upwardly on the screening in the panels, and are attracted toward the light, coming through the lower series of fly escape 20 passages 21 or 25 from the adjacent passage or cavity. These channels or cavities 18 and 22 are made sufficiently large relative to the size of the fly escape passages so as to admit sufficient light above the frame so that the 25 fly escape passages will be relatively inconspicuous compared to the size of such channels or cavities. After the flies enter the lower channel of either the panel rail or the upper rail, they are attracted toward the 30 light coming through the upper set of fly escape passages from the upper channel. These channels 19 and 23, are likewise made sufficiently large so as to admit sufficient light through the passages to attract the 35 flies, and also that the passages will be relatively inconspicuous compared to the size of these channels. The exact configuration of the channels or cavities is otherwise immaterial, although it is preferable to design 40 them of such a shape that no deep shadows will be formed therein and also that they may be readily cut therein by any ordinary shaper or other machine, assuming that the frame members are made of wood, or mate- 45 rial which may be similarly worked. For the purpose of illustration, the lower channels are semi-circular in cross section, and may be easily formed in the rails by a suitable cutter on any ordinary shaper. The 50 upper channels are shown as quadrant-shaped in cross section, and may be easily cut in the rail by a suitable cutter. The fly escape passages are also preferably of simple configuration, so that they may be easily cut 55 by hand or by machine. By utilizing channels and passages of simple configuration, so that they may be easily cut by machine, the increase in cost of manufacture of these rails over the cost of manufacture of rails for the 60 ordinary screen is practically negligible.

By providing a fly escape channel, such as channels 19 and 23, which opens on the face of the screen instead of the top edge, the construction in my former Patent No. 1,305,147, 65 granted May 27, 1919, is applied to a screen

adapted to fit within a frame which entirely surrounds the edges of the screen, including the top edge, such as a door frame. This construction also permits the application of the construction of my former patent to 70 screens having one or more panels. The upper margin 26 of the transverse panel rail provides means for attachment of the lower edge of the screening material of the next upper panel, and the gap between adjacent 75 panels of screening material permits the escape of flies which may be found upon any lower panel. Unless the lower panel is provided with means for permitting the escape of flies found on this panel, such flies are not 80 likely to escape even through the passages at the top of the screen because the panel rail forms an obstruction to their travel to the top of the screen.

I claim:

1. A fly escape screen, comprising in combination a screen frame adapted to fit within a door or similar opening, the top rail of said frame having a pair of vertically spaced cavities formed in the exterior face of 90 said rail and having passages relatively smaller than said cavities formed therein and connecting said cavities, screening material secured to the exterior of said frame and covering the lower cavity, said rail also 95 having fly escape openings formed therein leading from the lower cavity into the interior of the screen.

2. In a screen door or the like, the combination with a frame the upper rail of 100 which is provided in its exterior face with a cavity and fly escape passages above and below the same, and another cavity above the upper fly escape passage adapted to admit light thereto, and screening material for said frame secured to the exterior thereof and extending over the lower cavity and said fly escape passages.

3. In a fly escape screen, the combination 110 with a frame, of a transverse panel rail in said frame having transverse upper and lower channels formed in the exterior face thereof intermediate the adjacent edges, and fly escape passages formed therein leading 115 from the lower edge of said rail to said lower channel, and from said lower to said upper channel, the lower panel of screening material secured across the lower panel of said frame at the exterior thereof and 120 extending over said lower channel and said passages, and an upper panel of screening material secured across the upper panel of the frame and to the upper margin of said transverse rail.

4. In a fly escape screen, the combination 125 of a frame having a transverse panel rail therein dividing the same into a plurality of panels, screening material secured over the exterior of said frame and divided at 130

said transverse rail to form a gap, said transverse rail having fly escape passages in the outer face thereof and open to the light leading from the interior of the screen to 5 the exterior at said gap.

5. A fly escape screen of the type described comprising a frame having a rail thereon formed with a pair of spaced cavities in a vertical face thereof intermediate 10 the edges, fly escape passages connecting said cavities and leading from one of said cavities to the interior of said screen, the other of said cavities being open to the exterior, and screening material covering the

first named cavity and said fly escape passages. 15

6. In a fly escape screen of the type described comprising a frame having a rail provided in its outer face with a pair of vertically spaced cavities, fly escape passages connecting said cavities and other passages leading from the lower cavity to the interior of said screen, said cavities and 20 passages being open to the light and screening material covering said passages and said lower cavity. 25

GEORGE W. MITTELSTAEDT.
